Primary Examiner — Michael C Stout*Assistant Examiner* — Melvin L Davis(74) Attorney, Agent, or Firm — Aird & McBurney LP(57) CLAIM

The ornamental design for a fairy figurine as shown and described.

DESCRIPTION

FIG. 1 is a front view of a fairy figurine of the claimed design;

FIG. 2 is a right-side perspective view thereof;

FIG. 3 is a left-side perspective view thereof;

FIG. 4 is a right-side view thereof;

FIG. 5 is a left-side view thereof;

FIG. 6 is a rear view thereof;

FIG. 7 is a top view thereof; and,

FIG. 8 is a bottom view thereof.

The broken lines showing the fairy figurine are for the purpose of illustrating portions of the article that form no part of the claimed design.

1 Claim, 8 Drawing Sheets(56)
